(57) **CLAIM**

The ornamental design for a steering wheel, as shown and described.

DESCRIPTION

FIG. 1 is a left perspective view of a steering wheel according to our novel design, the right perspective view being mirror symmetrical;

FIG. 2 is a front view thereof;

FIG. 3 is a right side view thereof, the left side view being mirror symmetrical;

FIG. 4 is a bottom view thereof; and,

FIG. 5 is a top view thereof.

The broken lines which define the bounds of the claimed design form no part thereof.

1 Claim, 2 Drawing Sheets

FIG. 1

FIG. 2
